United States Patent Office

Des. 205,215
Patented July 12, 1966

205,215

DOOR HANDLE

Montgomery Ferar, Huntington Woods, and Charles R. Russell, Southfield, Mich., assignors to Whirlpool Corporation, a corporation of Delaware

Filed Sept. 20, 1965, Ser. No. 87,072

Term of patent 3½ years

(Cl. D10—8)

FIG. 1

FIG. 2

FIG. 3

FIGURE 1 is a side elevational view of a door handle, showing our new design.

FIGURE 2 is a front elevational view thereof.

FIGURE 3 is an end elevational view thereof.

FIGURE 4 is a sectional view taken substantially along line 4—4 of FIGURE 2.

FIGURE 5 is a sectional view taken substantially along line 5—5 of FIGURE 2.

We claim:

The ornamental design for a door handle, substantially as shown and described.
